UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed April 25, 1930. Serial No. 447,136.

My invention relates to car roofs of the all-steel riveted-up type wherein heavy gage roofing sheets extend from side plate to side plate of the car and are rigidly secured to each other by seam covers that function as carlines.

The principal object of the present invention is to increase the weatherproofing qualities of the roof at the eaves ends of the seams. Another object is to provide supporting brackets for the sheets at the eaves ends of the seams and to utilize such brackets as supports for load lifting attachments and as a means for carrying off any water that may enter the eaves ends of said seams. Other objects are simplicity and cheapness of construction and compactness of design.

The invention consists in the car roof and in the construction, combinations and arrangements of parts hereinafter described and claimed.

In the accompanying drawings, which form part of this specification and wherein like symbols refer to like parts wherever they occur,

Fig. 1 is a plan view of a portion of car roof embodying my invention,

Fig. 2 is an enlarged fragmentary plan view of the roof in the region of the eaves end of one of the seams, a portion of the seam cover being shown broken away to disclose parts located therebeneath,

Fig. 3 is a plan view of one of the sheet supporting brackets,

Fig. 4 is a vertical cross-section through the eaves portion of the roof on the line 4-4 in Fig. 1,

Fig. 5 is a vertical cross-section through one of the seams on the line 5-5 in Fig. 4,

Fig. 6 is a similar cross-section through said seam on the line 6-6 in Fig. 4, and

Fig. 7 is a horizontal cross-section on the line 7-7 in Fig. 4.

Referring to the accompanying drawings, my invention is shown in connection with a car having Z-bar side plates 1 arranged with their webs horizontal and with their inner flanges extending upwardly. Metal roof sheets 2 extend transversely of the car from side plate to side plate and slope downwardly on opposite sides of the ridge to the eaves.

The side marginal portions of the roof sheets are offset upwardly to form raised side panels 3 which gradually increase in width from the ridge to the eaves ends of said sheets. The free marginal edges of the raised side panels 3 of the roof sheets are bent up to form upstanding side seam flanges 4 that extend from end to end of the sheet. At the eaves, the entire end portions of the roof sheets, including the side panels 3 and the side seam flanges 4, are turned down to form depending eaves flanges 5 that overhang and are rigidly secured to the upstanding inner flanges of the side plates 1 preferably by rivets 6. As shown in the drawings the depth of the eaves end portions of the side seam flanges 4 are reduced as at 4a, so as to prevent rupture of the metal or galvanizing when the flanges are bent down with the body of the sheets to form the depending eaves flanges 5 thereof.

The adjacent side seam flanges 4 of the roof sheets are covered by weather-proofing members, preferably in the form of inverted U-shaped seam covers or carline caps 7, which extend from eaves to eaves of the car and are rigidly secured to said sheet flanges by rows or rivets 8. The hollow ribs of the seam covers are preferably of greater depth at the ridge than at the eaves, each rib decreasing in depth uniformly from the ridge to points adjacent to the eaves where they slope downwardly and are turned down over down-turned ends of the side seam flanges 3 of adjacent roof sheets. The seam covers are provided at the lower edges of the side walls of their hollow ribs with outstanding base flanges 9 that bear against the raised side panels 3 of adjacent roof sheets and are turned down over the depending eaves flanges 5 of said sheets and secured to the side plates by the rivets 6. The hollow ribs of the seam covers 7 are preferably of greater height at the ridge than at the eaves, and their base flanges 9 are wider at the eaves than at the ridge. As shown in the drawings, the width of the hollow rib of each seam cover is increased, as at 10, at the eaves so that their walls are spaced away from the inner faces of the side seam flanges 100.

4 of the roof sheets from points located just inside the side plates to the lower ends of the downwardly extending eaves portions of said flanges.

5 By the arrangement described, the side seam flanges 4 of the roof sheets, instead of terminating where the sheets are turned down to form the depending eaves flanges 5, are bent down with said eaves flanges there-
10 by preventing water that is forced between the base flanges 9 of the seam covers 7 and the side panels 3 of the roof sheets from entering the car where the sheets and seam covers are turned down. The tendency for
15 the water to creep over the shallow end portions 4a of the side seam flanges 4 by capillary attraction is prevented by the widened ends 10 of the hollow ribs of the seam covers 7 which serve to space apart the eaves end
20 portions of said side seam flanges and the side walls of said hollow ribs.

Located beneath the roof sheets at the eaves ends of the seams are angle-shaped supporting brackets 11. The vertical flange 25 of each sheet supporting bracket is positioned between the upstanding inner flange of the side plate, and the downturned end of the side panels 3 of adjacent roof sheet and is secured in position by the rivets 6. The
30 other flange of said bracket extends inwardly beneath the side panels of adjacent roof sheets and is secured flatwise thereto and to the base flanges 9 of the seam cover 7 by rivets 12. The inwardly extending flange of
35 the sheet supporting bracket 11 has a central channel 13 pressed therein which slopes downwardly from the inner end portion of said flange to the depending vertical flange of said bracket. By this arrangement, any
40 water that may be forced over the shallow end portions 4a of the side seam flanges 4 of the roof sheets will be deposited in the channel in the sheet supporting bracket and discharged through the lower, open end of the
45 downturned end of the rib of the seam cover.

Secured to the under side of the inwardly extending flange of each sheet supporting bracket 11 is a support for a suitable load lifting device. As shown in the drawings, 50 said support comprises a channel shaped member 14 provided at the top of its walls with outstanding flanges 15 that are riveted or otherwise secured flatwise to the inner side of the inwardly projecting flange of the
55 sheet supporting bracket 11. The channel portion of said member 14 extends longitudinally of the inwardly extending flange of the sheet supporting bracket 11, and the web of said channel is convexly curved from end to end so as to present a rounded surface to prevent chaffing or wear of the chain or rope of the load lifting device.

As shown in the drawings, plates 16 are interposed between the adjacent side seam flanges 4 of the roof sheets for the purpose

of supporting a load lifting device (not shown) at the center of the car. It is noted that such plates are used in roofs for automobile cars; but in roofs for ordinary box cars the plates are usually omitted and the 70 side seam flanges of the sheets secured together in contact with each other.

The invention is adapted for use with cars having various forms of side plate constructions, and I do not wish to be limited to the 75 precise construction shown and described.

What I claim is:

1. A rigid car roof comprising side plates, roof sheets extending from side plate to side plate, said roof sheets being provided along their adjacent margins with upstanding seam flanges, said seam flanges being of reduced depth at the eaves of the car, and seam covers straddling adjacent seam flanges, said seam covers closely embracing and rigidly secured 80 to the deep portions of said seam flanges and being spaced away from the shallow eaves portions thereof in directions transverse thereto.

2. A rigid car roof comprising side plates, roof sheets extending from side plate to side plate, said roof sheets being provided along their adjacent margins with upstanding seam flanges having eaves end portions of reduced depth that are turned down over the side plates, and seam covers straddling adjacent seam flanges and rigidly secured thereto and having their eaves end portions turned down over the adjacent flanged margins of said roof sheets.

3. A rigid car roof comprising side plates, roof sheets extending from side plate to side plate, said roof sheets being provided along their adjacent margins with upstanding seam flanges having eaves end portions of reduced depth that are turned down over the side plates, and seam covers straddling adjacent seam flanges and rigidly secured thereto and having their eaves end portions turned down over the adjacent flanged margin of said roof sheets, said seam covers closely embracing the deep portions of said seam flanges and being spaced away from the shallow eaves portions thereof in directions transverse thereto.

4. A rigid car roof comprising side plates, roof sheets extending from side plate to side plate, said roof sheets being provided along their adjacent margins with upstanding seam flanges having eaves end portions of reduced depth that are turned down over the side plates, and seam covers straddling adjacent seam flanges and being rigidly secured thereto and having shallow eaves end portions that are turned down over the adjacent margins of the downturned eaves ends of said sheets, said seam covers closely embracing the deep portions of said seam flanges and being spaced away from the shallow downturned eaves end portions thereof in directions transverse thereto.

5. A car roof comprising side plates, roof sheets extending from side plate to side plate, said roof sheets being provided along their adjacent margins with upstanding seam flanges having eaves end portions of reduced depth that are turned down over the side plates, and seam covers straddling adjacent seam flanges and having shallow eaves end portions that are turned down over the adjacent margins of the downturned eaves ends of said sheets, said seam covers closely embracing the deep portions of said seam flanges and being spaced away from the shallow downturned eaves end portions thereof in directions transverse thereto, and sheet supporting brackets secured to the side plates beneath the shallow eaves end portions of adjacent seam flanges and provided with drain channels communicating with the downturned eaves ends of said seam covers. 70
6. A car roof comprising Z-bar side plates arranged with their webs horizontal and one flange in and extending upwardly, roof sheets extending from side plate to side plate with their eaves end portions turned down and rigidly secured to the outer faces of the upstanding inner flanges thereof, said roof sheets being provided along their adjacent margins with upstanding seam flanges, seam covers straddling adjacent seam flanges with their eaves end portions turned down over the downturned eaves ends of said roof sheets and rigidly secured to the upstanding flanges of said side plates, and sheet supporting brackets located beneath adjacent margins of the sheets of the eaves, said brackets comprising a depending flange secured to the inner flange of a side plate between said flange and the downturned portions of adjacent sheets and a sheet supporting flange extending inwardly over said side plate flange and provided below said seam flanges with a drain channel communicating with the downturned end of the seam cover, and means on said sheet supporting flange for supporting a load lifting device, said drain channel forming a gusset for strengthening said bracket to enable it to carry the load suspended from said load lifting device. 80
7. A roof sheet supporting bracket having a flange adapted to be secured to a side plate and a flange adapted to support adjacent roof sheets, said sheet supporting flange having a longitudinal drain channel pressed in the upper surface thereof which forms a gusset between said flanges. 85
8. A roof sheet supporting bracket having a flange adapted to be secured to a side plate and a flange adapted to support adjacent roof sheets, and means secured to the underside of said sheet supporting flange for supporting a load lifting device, said sheet supporting flange having a longitudinal drain channel pressed in the upper surface thereof which forms a gusset for strengthening said bracket 90
- to enable it to carry the load suspended from said load lifting device. 95
